ELECTRICAL DEVICE COVER PLATE

Robert E. V. Ramsing, 15283 El Soneto, Whittier, Calif.

Filed Oct. 14, 1963, Ser. No. 76,957

Term of patent 14 years

(Cl. D26—13)

FIG. 1.

FIG. 2.

FIG. 3.

FIG. 4.

FIG. 5.

FIG. 1 is a view showing in front elevation an electric device cover plate embodying my new design;

FIG. 2 is a top plan view of FIG. 1;

FIG. 3 is a bottom plan view of FIG. 1;

FIG. 4 is a left side elevation of FIG. 1; and

FIG. 5 is a right side elevation of FIG. 1.

I claim:

The ornamental design for an electrical device cover plate, substantially as shown.
